UNITED STATES PATENT OFFICE.

STEWART P. COLEMAN, OF CAMBRIDGE, MASSACHUSETTS, AND WAYNE S. HUGHES, OF GOOSE CREEK, TEXAS, ASSIGNEES TO STANDARD OIL DEVELOPMENT COMPANY, A CORPORATION OF DELAWARE.

RECLAIMING DISTILLATION RESIDUES.

Application filed February 7, 1924. Serial No. 691,162.

This invention relates to the art of reclaiming distillation residues and more particularly such residues as are left in redistilling lubricating stocks which contain 5 naphthenic compounds. The invention will be understood from the following description taken in connection with the accompanying drawing which represents an isometric view of one form of apparatus contemplated.

Where lubricating stocks containing naphthenic acids are redistilled in the presence of caustic soda or other sodium compound, a heavy residue comprising an intimate mixture of sodium naphthenate or other naphthenates and high viscosity oil is left in the still. Heretofore such residues have been thought useful only for admixture with fuel oil. In accordance 20 with the present invention, however, we are enabled to reclaim such residues and derive therefrom a lubricating oil stock of higher viscosity and desirable properties otherwise, and also naphthenic compounds 25 which are capable of various uses.

In carrying out the invention we take the residue, preferably as it is drawn hot from the still, and flow it upon a moving stream of water. The velocity of the water stream 30 should not be such as to cause turbulence or mixing, but on the contrary is advisably of such gentle character that the oily residue discharged thereon may quietly spread out over its surface and be carried along without risk of emulsification. An advantageous form of apparatus for the practicing 35 of this process is represented in the drawing in which the reference numeral 1 designates a trough having at its end a means 40 for a supply of water, illustrated as a pipe 2 with control valve 3. Further along in the trough is a discharge means for a distillation residue, illustrated as a pipe 4 with control valve 5, the pipe preferably 45 having a spray-head or slotted-head discharge so as to effect as thorough a spread of the residue upon the water surface as feasible. The trough discharges into a settling tank 6, a dam 7 being provided to 50 maintain a fixed water level in the trough,

and an apron 8 to prevent currents at the point of discharge into the tank. The settling tank may vary considerably in its form and dimension, but an advantageous layout is illustrated in the drawing in that 55 it is so arranged as to conserve space and yet accomplish a feasible stratification of the ingredients of the residue. To this end the baffles 9, 10 and 11 are arranged in the tank in laterally staggered order so as to 60 compel the contained liquids to travel very slowly and free from turbulence to the respective points of discharge. Valve-controlled draw-off pipes 12 and 13 are arranged at the bottom of the tank, and from 65 a point near its top a draw-off pipe 14 leads to discharge into a second tank 15. Along the bottom of the second tank a suitable heating means is arranged, illustrated 70 in the drawing, for instance, as a steam coil 16. A valve-controlled draw-off pipe 17 is provided at the bottom of this tank and an adjustable swing draw-off pipe 18 at the top.

A current of water being provided in the 75 trough by the water inlet pipe 2, the distillation residue is discharged gently upon the surface of the water through the pipe 4, and the flowing water and supernatant oily residuum is passed along into the settling 80 tank where a stratification into layers takes place, the lower layer consisting of water and dissolved naphthenates. On coming in contact with the water, the water-soluble naphthenates rapidly dissolve out from the 85 oily mixture and go into the water. At the start sufficient water is primarily supplied to the tank to bring the level up well to the top and after the feed of residuum is established and stratification into layers has 90 taken place, the lower layer is drawn off at such a rate as to allow an adequate accumulation of the upper layers, permitting suitable draw-off thereof into the second tank 95 15. By proper regulation of the draw-off valves the process may thus be made to function in continuous manner, the stratification levels being maintained at relatively constant points. The oil layer and some naphthenic compounds pass over to the 100

second tank, and here final stratification and separation allows of the withdrawing of the clean oil from the top, the swing pipe 18 by its vertical adjustability allowing of 5 the taking off of the oil only. From the bottom of the tank the naphthenic compounds, occurring here chiefly as naphthenates of the heavy metals, especially iron, are withdrawn for further treatment. 10 This treatment may vary somewhat, but preferably would comprise the subjecting of the naphthenate mixture, it being in the form of emulsion, to the action of sulphuric acid. This serves to decompose the naphthenates and set free the naphthenic acid 15 and the emulsified oil, and on settling, these constituents can be drawn off from the top and the sludge be run to waste.

It will be understood, however, that the 20 naphthenates of the heavy metal form such a minor component of the distillation residue that in many cases it is not worth while attempting a separate separation and treatment of these, but the separation may 25 proceed along the main lines of division of the oil on the one hand and the water-soluble naphthenates on the other. The water-soluble naphthenates may be recovered from the water by salting out or by concentration, 30 and these compounds are then available for various uses as desired.

If preferred, the stratification levels can be so maintained that the heavy metal 35 emulsified naphthenic layer may be drawn off from tank 6 and further separated, as mentioned in the foregoing, instead of being carried over into tank 15 and thence being separated off; that is, the precise point at which the separation of the heavy metal

emulsified naphthenate layer occurs is a 40 matter of choice in operating detail.

What we claim is:

1. The process of reclaiming naphthenic distillation residues, which comprises discharging the hot residue onto the surface of 45 flowing water, then allowing stratification into layers to occur, withdrawing the water and dissolved naphthenate from the bottom layer, subjecting the residual material to further stratification, withdrawing the oil 50 from the top and withdrawing the water containing metal naphthenates from the bottom layer.

2. The process of reclaiming naphthenic distillation residues, which comprises discharging the hot residue onto the surface of 55 flowing water, then allowing stratification into layers to occur, withdrawing the water and dissolved naphthenate from the bottom layer and withdrawing the oil from the 60 top.

3. The process of reclaiming naphthenic distillation residues, which comprises discharging the residue onto the surface of gently moving water, then retarding the 65 flow and allowing stratification into layers to occur, and separately withdrawing the water and dissolved naphthenate from the bottom layer and the oil from the top.

4. The process of reclaiming naphthenic 70 distillation residues, which comprises discharging the residue onto the surface of moving water, and allowing stratification into layers and separately withdrawing the water and dissolved naphthenate in one 75 layer and the oil in the other.
